CLAIM

The ornamental design for a dice, as shown and described.

DESCRIPTION

FIG. 1 is a perspective view of a dice illustrating my new design;

FIG. 2 is a front view of the dice;

FIG. 3 is a rear view of the dice;

FIG. 4 is a left side view of the dice;

FIG. 5 is a right side view of the dice;

FIG. 6 is a top view of the dice; and,

FIG. 7 is a bottom view of the dice.

The broken lines shown in the drawings are for the purpose of illustrating environmental structure, which form no part of the claimed design.
